UNITED STATES PATENT OFFICE.

BERTRAND B. KAHN, OF CINCINNATI, OHIO, ASSIGNOR TO THE ESTATE STOVE COMPANY, OF HAMILTON, OHIO.

CHAPLET-MACHINE.

1,111,750.

Specification of Letters Patent. Patented Sept. 29, 1914.

Application filed December 24, 1913. Serial No. 808,518.

To all whom it may concern:

Be it known that I, BERTRAND B. KAHN, a citizen of the United States, residing in the city of Cincinnati, Hamilton county, Ohio, have invented certain new and useful Improvements in Chaplet-Machines, of which the following is a specification.

This invention relates to a machine for forming chaplets, for foundry uses, by the bending up of sheet-metal.

My invention will be readily understood from the following description taken in connection with the accompanying drawings in which—

15 Figure 1 is a front elevation of a chaplet machine exemplifying my improvement; Fig. 2 a side elevation of the same (right hand side of Fig. 1) with the receiving table omitted; Fig. 3 a vertical section of the shear in the plane of line *a* of Fig. 2; Fig. 20 4 a vertical section of the machine in the plane of line *b* of Figs. 1, 5, 6 and 7; Fig. 5 a front elevation of the main cam, its shaft appearing in vertical transverse section in the plane of line *c* of Figs. 2 and 4; Fig. 6 a plan of the main cam and stripper; Fig. 7 a rear elevation of the main cam and the wipers, parts appearing in vertical section in the planes of lines *d* and *e* of Fig. 2; Fig. 8 a plan of the active portion of the wiper; Fig. 9 a perspective view of the product of the machine in the form of a chaplet entirely rectangular in form and made of perforated metal and provided with 35 a vertical central bridge; Fig. 10 a perspective view of a similar chaplet minus the perforations and the bridge; Fig. 11 a perspective view of a chaplet having curved walls; and Figs. 12 to 16, inclusive, views 40 illustrating the progressive steps in the formation of the chaplet illustrated in Fig. 9.

I will first describe examples of the chaplets to be produced and will describe, in a general way and without reference to particular instrumentalities, the method of forming the chaplets.

In the drawings and referring for the present only to Figs. 9 to 16 inclusive—1, indicates a chaplet of rectangular form and of 45 perforated metal bent up in the form of a box of decided dimension and open at two opposite sides, the metal projecting inwardly from one end wall being over-lapped by metal projecting inwardly from the opposite wall; 2, a bridge formed by bending

down the inner end of the lowermost of the lapping part of the walls, the lower end of this bridge bearing against the wall opposite the wall having the over-lap; 3, a chaplet similarly formed except that it has no bridge and no perforations; 4, a chaplet similar to those before mentioned except that its walls are curved; 5, the bridge of this curved chaplet; 6, a strip of proper dimension to form the given chaplet; 7, the strip after it has been bent up to form the bottom wall and the two end walls of the chaplet; 8, the strip after one of the up-standing portions has been turned inward to form part of the top wall; 9, the same when the inner end of the top-wall has been turned down to form the bridge 2 and 10, the completed chaplet formed by bending down a portion of the remaining up-standing wall of the example 9 so that its inner end will underlie the previously formed portion of the top-wall.

My present machine is designed to accomplish the various mentioned turns of the strip. It is immaterial so far as my machine is concerned, whether the metal be perforated or plain, and the machine is adapted for the making of chaplets with or without bridges and of curved or straight form, and of various dimensions or shapes differing from the illustrated examples, according to the character of the functional tools. I will now describe the immediate instrumentalities by means of which this work is done, not much attention being paid at present to the mechanism but giving functional motion to these instruments.

Proceeding with the drawings:—11, indicates the frame of the machine, of general columnar form; 12, a knee at the front of the base thereof; 13, a bed-die supported separably in a die holder on the knee; 14, a table at the feeding side of the machine, with its upper surface level with the top of the bed-die; 15, a lower shear-blade at the feeding side of the bed-die and substantially even with the top of the bed-die; 16, a top shear-blade to co-operate with the lower shear-blade; 17, a stop projecting up from the bed-die such distance from the cutting plane of the shear-blades as corresponds with the length of the strip of metal employed in forming the chaplet, such as the strip 6, of Fig. 12; 18, a recess in the upper surface of the bed-die, this recess forming the bed-

die proper and having a form suited for the pressing of the chaplet, the recess being illustrated as suited to the formation of such rectangular chaplets as are illustrated in Figs. 9, 10 and 16: 19, a cross-head mounted to reciprocate in the frame, to the rear of the bed-die: 20, a core-die, projecting forward from cross-head 19, and over the bed-die, this core-die being of a form adapted for the interior of the chaplet to be produced and being slotted fore and aft for the bridge 2, if the chaplet is to have a bridge: 21, a circular block on the rear end of the core-die, this block fitting a circular recess in the cross-head 19, and serving as means for holding the core-die in that cross-head and for permitting its ready removal and renewal and substitution: 22, a set-screw in the cross-head 19, to serve as a binder for the block 21, in holding the core-die firmly in the cross-head: 23, a wiper, illustrated as being pivoted to the frame, adapted to move in over and on the top of the feeding side of the bed-die and over the recess 18, this 25 wiper or folder having a fore and aft width equal at least to that of the strip of metal to be dealt with, this wiper being disposed in the plane of the rear part of the bed-die, the bed-die and core-die having longitudinal 30 dimensions equal at least to twice the width of the strip to be dealt with: 23^a, a wiper similar to wiper 23 but crossing inwardly over the non-feeding side of the machine, this wiper being disposed in front of the 35 wiper 23 so that the two may overlap over the bed-die: 24, a second cross-head mounted for vertical reciprocation in front of cross-head 19, cross-head 24, being hereinafter spoken of as the main cross-head while cross-head 19 will be spoken of as the secondary cross-head: 25, a top-die carried at the base of the main cross-head over the core-die and the recess in the bed-die and adapted to engage the top of the core-die: 26, a longitudinal strip carried by the lower surface of the top-die and adapted to freely enter the slot in the core-die: 27, a flange projecting forward from the secondary cross-head through a vertical recess in main cross-head 24, which 40 recess is of considerable height: 28, a helical spring disposed in the recess of the main cross-head and acting compressively between flange 27 and the roof in the recess of the main cross-head: 29, an adjusting nut threaded on a vertical stud projecting up from flange 27, this nut being in position between the flange and the foot of the spring: 30, a spring having its heel secured to table 14 and having its forward end near 45 the outer face of the top shear-blade: 31, a loop carried by the forward end of this spring, this loop being of a size to permit the strip of stock to pass through it on its way to the shear-blade, and the disposition and tension of the spring being such as to

suspend the advancing end of the strip of stock above the level of the lower shear-blade, the upper portion of the loop being below the outer portion of the upper shear-blade: 32, a stripper surrounding core-die 21 and normally lying at the rear of the core-die or at the front face of the secondary cross-die: 33, a horizontally reciprocating stripper frame mounted in the main frame and carrying the stripper blade at its forward end. 70

In the operation of the parts thus far referred to a long strip of stock is to be fed in over the table, resting on spring 30 and under the top of loop 31 and between the shear-blades and over the bed-die, its advancing end being arrested by stop 17. The elevation of the advancing end of the strip by the spring prevents that end from catching against the lower shear-blade. The upper shear-blade now descends, forces down the spring and shears off the strip leaving on the bed-die a short strip of proper length to form a chaplet. The core-die now descends upon the middle portion of this strip and presses that portion of it down into the recess of the bed-die causing the ends of the strip to turn up as indicated in Fig. 13. Wiper 23 now moves inwardly causing the strip to be bent to the form indicated in Fig. 14, the wiper at once retreating. Top-die 25 now descends, its base nicely completing the bend effected by wiper 23, strip 26 on the top-die at the same time bending the inner portion of the inbent metal down through the slot in the core-die and forming the bridge 2 of the chaplet. The top-die now rises and stripper 32 advances and pushes the partly formed chaplet forward on the core-die and into the main forward portion of the recess in the bed-die. Wiper 23^a now moves in and bends the vertical upstanding portion of the strip inwardly over the core-die, and then retreats. The top-die, in descending again, gives exactness and completion to this second fold of the metal, it being understood that the strip 26 on the top-die does not extend fully forward in the low portion of the bed-die. This completes the chaplet, and when the next forming chaplet is pushed forward by the stripper it will push the chaplet off of the core-die and discharge it. The arrangement of the machine is such that the two wipers move simultaneously, the rear wiper 23 acting on one forming chaplet while the front wiper 23^a acts on the partly formed chaplet which has been pushed forward by the stripper. An operation is thus being performed by the forming instruments on two chaplets at once, and each impulse of the instruments bring about the completion of one chaplet. 115

Explanation will now be made of the actuating mechanism for giving functional motion to the instrumentality, and atten- 130

tion will be first given to the mechanism for actuating the cross-head.

Proceeding with the drawings:—34, indicates a crank-shaft journaled fore and aft in the top of the frame and adapted to be rotated continuously by power: 35, a crank on the forward end of the crank-shaft: and 36, a connecting-rod connecting the crank-pin with a wrist in the main cross-head.

- 10 The crank depresses the main cross-head, and the main cross-head, acting through the medium of the spring 28, pushes the secondary cross-head down simultaneously. When the core-die has bent the metal down 15 into the bed-die then the core-die and the secondary cross-head, being unable to descend comes to rest. The main cross-head continues its stroke, the yielding of spring 28 permitting this, and the top-die is forced 20 down to the core-die to complete the work of the core-die. Spring 28, while capable of yielding when the core-die begins its motion, is to be strong enough to force the core-die down to its work, adjusting nut 29 permitting 25 the tension of the spring to be adjusted as needed.

I will now describe the mechanism for actuating the upper shear-blade.

Proceeding with the drawings:—37, indicates a rock-shaft journaled in the front of the base of the machine under the heel of the upper shear-blade: 38, an arm splined on this rock-shaft and projecting forward under a forwardly projecting arm of the upper shear-blade: 39, a link connecting the forward extremity of the arm 38 with the forward projecting arm of the shear-blade: 40, a rearwardly projecting arm secured to the rock-shaft 37: 41, a spring holding the rear 40 end of this arm up and holding the upper shear-blade up: 42, a cam on the crank-shaft over the rear end of arm 40: 43, a vertical rod having its lower end in engagement on arm 40, and having its upper end in engagement with cam 42, the upper end of the rod being preferably provided with an anti-friction roller where it engages the periphery of the cam: and 44, a helical spring surrounding rod 43 and sustaining the weight of that 45 rod and maintaining its upper end in engagement with the cam and taking the weight of the rod off of arm 40.

At each turn of the crank-shaft the upper shear-blade descends and shears off the strip of stock, as has been heretofore mentioned. Shear-cam 42 is to be so timed that this shearing will take place before the core-die has descended upon the stock. The length of stock required for various sizes and forms 55 of chaplets will vary and this variation will in most cases call for an appropriate width of bed-die with appropriate position for stop 60 17 and the lower shear-blade. As the change in the position of the lower shear-blade calls 65 for a corresponding lateral shifting of the

upper shear-blade, such shifting is taken care of by adjusting arm 38 along shaft 37.

Attention will now be given to the mechanism for actuating the two wipers.

Proceeding with the drawings:—45, indicates a pair of rock-shafts mounted in the main frame of the machine, one at each side of and below the bed-die, each of these rock-shafts having attached to it one of the wipers 23, 23^a, the relation of parts being such that 75 the rocking of the shaft will cause the active ends of the wipers to swing inwardly and downwardly to effect the inward and downward bending of the metal as heretofore explained: 46, a cam fast on the crank-shaft: 47, a vertical sliding rod disposed below this cam and having its upper end in engagement with the cam, and, preferably armed with an anti-friction roller: 48, a horizontally sliding yoke on the lower end of this rod, which rod slides through a suitable vertical bearing in the frame: 49, a collar fast on the rod, below its bearings: 50, a spring coiled on the rod between this collar and the bearing: 51, arms fast on rock-shafts 45, and 80 having each a pin engaging the slot of yoke 48: and 52, a spring coiled on the rod 47, above its bearing and serving to elevate the 85 rod.

Normally the parts of the wiper mechanism will be in the position indicated in Fig. 7, the yoke being in its uppermost position and the rod being held up to the cam by spring 52, the wipers being in their outermost positions. At each turn of the cam its 95 active cam-elements force the rod and yoke quickly down and causes the wiper to move inwardly and do the work upon the metal as before explained, the wipers then separating and the yoke and rod rising again to 100 normal position, spring 50 elastically retarding the upstroke of the rod and prevents its upper end from impactively striking the cam.

Attention will now be given to the illustrated mechanism for actuating the stripper 110 per 32.

Proceeding with the drawings:—53, indicates a vertical rock-shaft mounted on the rear of the machine to one side of stripper-frame 33: 54, arms projecting from this rock-shaft and having slotted extremities straddling stripper-frame 33, and engaging a pin thereon, so that, as the shaft is rocked, the arms will oscillate and reciprocate the 115 stripper-frame and stripper: 55, a spring coiled upon rock-shaft 53, and acting torsionally to hold the rock-shaft in position corresponding with the normal idle rear position of the stripper: 56, an arm projecting 120 from rock-shaft 53, to near the front face of cam 46: 57, a conical roller mounted on the front face of cam 46, with its axis parallel with the face of the cam, this roller being adapted, at each turn of the cam, to engage 125 130

arm 56, and rock-shaft 53, and push the stripper forward on the core-die; 58, a carriage supporting roller 57, and mounted for radial adjustment on the face of the cam 5, 59, a pulley mounted on the crank-shaft to serve as means through which the machine may be operated by belt power; and 60, the strip of metal being fed into the machine.

At each turn of the crank-shaft the roller 10 57 rocks shaft 53, and forces the stripper out on the core-die, spring 55 returning the stripper to normal position as soon as the roller shall have past the arm. The normal position of the stripper is back against the 15 secondary cross-head, and the extent of the active stroke of the stripper may be adjusted, in an obvious manner by shifting roller 57, radially on the cam. The stripper will require to have an active stroke increased in extent when the width of stock being dealt with is increased.

Description has been given of the bends to be produced upon the metal, and of the instruments for doing the work, and of the 25 mechanism for giving the instruments their functional motion. The movements of the parts are to be so timed, relative to each other, that, a strip of stock having been run in over the bed-die, the shear closes, leaving 30 a strip of proper length upon the rear portion of the bed-die; the core-die descends and bends the metal down into the bed-die; the rear-most wiper bends one up-standing portion of the metal down over the core-die, 35 and retreats; the top-die descends and bends the portion down from this inturned portion of the top-wall; the stripper pushes the partly completed chaplet forward on the core-die; this moving forward of the partly 40 completed chaplet pushes off of the core-die a previously completed chaplet. As the rear-most wiper moves inward to bend down one up-standing wall of metal, the fore-most wiper bends inward the second up-standing 45 wall of the chaplet which has been pushed forward upon the core-die, and the top-die in descending to bend the bridge upon the metal of the first chaplet and to move completely if necessary, press down the top-wall 50 portion from which the bridge is formed, simultaneously presses down the second up-standing wall of the chaplet which has been shifted forwardly upon the core-die and had its second up-standing wall bent inwardly 55 by the forward wiper.

In the construction and operation of the machine as thus far referred to, provision is made for operating simultaneously on the upper bends of two chaplets, one of which 60 has been pushed forward into the front field of operation of the second wiper. Under this mode of operation the wipers would have the general construction illustrated in Fig. 8, one being forward of the other. 65 These wipers do not or need not move in-

ward as far as the center of the chaplet, it being sufficient that they move far enough to bend down the upstanding sides of the chaplet. The consequence is that in certain forms of chaplets, such for instance as that 70 illustrated in Fig. 10, the two wipers may act simultaneously upon one chaplet, the active end of the forward wiper in such case being disposed rearward as indicated at 23^b in Fig. 8. But in case the chaplet is to 75 have a bridge to be bent down by the strip 26 on the lower face of the top-die, other provision must be made if it be desired to have the top-die act on the bent-down portions so as to flatten the top of the chaplet. 80 Such other provision is made, as will be later explained, and consists, generally stated, in shifting the chaplet forward on the core-die after the side walls have been turned in, and then causing the chaplet to be 85 acted upon by the succeeding stroke of the top-die.

It has been explained, in connection with Fig. 4, that the crank pushes the main cross-head down, the main crosshead simultaneously pushing the secondary crosshead down until the latter is arrested, the spring 28 permitting the main cross-head to continue its descent, the tension of spring 28 being sufficient to cause the core-die to do its bending work. It will be obvious that the upper end of spring 28 need not abut against the main crosshead, a fixed abutment being sufficient, the duty of the main crosshead, in its action on the secondary crosshead, being to 90 lift the secondary crosshead and to permit of its descent at proper time. If the secondary crosshead was of sufficient weight to cause the cross-die to do its bending work then spring 28 would be quite unnecessary and, of course, it will be obvious that, while in the illustrated example, the secondary crosshead is lifted and sustained by the main crosshead, thus utilizing the actuating mechanism of the main crosshead, 95 such lifting and sustaining can be done by any other suitable mechanism for lifting and sustaining and lowering the secondary crosshead in proper time.

In the illustrated example the stripper 115 pushes a partially formed chaplet forward on the core-die, and the core-die is of length considerable in excess of the width of the chaplet. If the chaplet is not to have a bridge, or if it is not to be shifted forward 120 for a second bending operation upon it, then, of course, the core-die need have a length only to the width of the chaplet, and the stripper would become merely an agent for discharging the chaplet from the machine. 125

It will, of course, be understood that the invention comprehended herein, while designed particularly for the forming of chaplets for founders' use, may be of utility in the formation of articles other than foun- 130

ders' chaplets and that the invention will lend itself to the formation of chaplets and other articles of various forms other than the examples particularly illustrated. It 5 will also be apprehended that the mechanism illustrated will, at the hands of the skilled machine constructor, lend itself to various modifications without departing from the spirit of my invention. I am seeking simply to set forth the principle of my invention and the best form in which I at 10 present contemplate embodying that principle.

I claim:

- 15 1. A chaplet machine comprising, a bed-die having in its upper surface a recess adapted to the bottom and end walls of the chaplet to be produced, a longitudinally slotted core-die extending transversely 20 across the bed-die and adapted to move downwardly into the recess thereof and bend a strip of metal overlying the recess to form the bottom and upstanding walls of the chaplet, wipers disposed above the bed-die and at the sides of said recess and adapted to move inward and bend down 25 said upstanding walls to form the top of the chaplet, a vertically movable strip disposed above the recess and adapted to bend the inner end of one of the walls downward through the slot in the core-die, and mechanism for moving the core-die and strip and wipers, combined substantially as set forth.
2. A chaplet machine comprising, a bed-die having in its upper surface a recess having a depth equal to the vertical height of the chaplet to be produced and adapted to the bottom and end walls of the chaplet to be produced, a core-die extending trans- 35 versely across the bed-die and having a vertical dimension equal to the depth of said recess and adapted to move downwardly into the recess thereof and bend a strip of metal overlying the recess to form the bottom and 40 upstanding walls of the chaplet, wipers disposed above the bed-die and at the sides of said recess and adapted to move inwardly and downwardly and bend down said upstanding walls to form the top of the chaplet, a shear disposed across the top 45 of the bed-die at its stock-entering end, a stop projecting up from the face of the bed-die on the opposite side of the recess, and serving to arrest the advance of a strip 50 fed forwardly over the bed-die, and mechanism for moving the core-die and shear and wipers, combined substantially as set forth.
3. A chaplet machine comprising, a bed- 55 die having in its upper surface a recess adapted to the bottom and end walls of the chaplet to be produced, a core-die extending transversely across the bed-die and adapted to move downwardly into the recess 60 thereof and bend a strip of metal overlying

the recess to form the bottom and upstanding walls of the chaplet, wipers disposed above the bed-die and at the sides of said recess and adapted to move inward and bend down said upstanding walls to form 70 the top of the chaplet, a perforated stripper surrounding and sliding on said core-die and movable outwardly thereon, and mechanism for moving the core-die and stripper and wipers, combined substantially 75 as set forth.

4. A chaplet machine comprising, a bed-die having a width equal at least to twice the width of the strip of metal from which the chaplet is to be made and having in 80 its upper surface a recess adapted to the bottom and end walls of the chaplet to be produced, a core-die extending transversely across the width of the bed-die and adapted to move downwardly into the recess thereof 85 and bend a strip of metal overlying the recess to form the bottom and upstanding walls of the chaplet, a wiper disposed above the bed-die and at one side of said recess and adapted to move inward over the rear 90 of the bed-die and bend down one of said upstanding walls so as to form a portion of the top of the chaplet, a wiper disposed above the bed-die at the side of the recess opposite the first-mentioned wiper and 95 adapted to move inward and bend down the remaining upstanding wall of the chaplet whose first upstanding wall was bent down by the first-mentioned wiper, and mechanism for moving the core-die and 100 wipers, combined substantially as set forth.

5. A chaplet machine comprising, a bed-die having a width equal at least to twice the width of the strip of metal from which the chaplet is to be made and having in 105 its upper surface a recess adapted to the bottom and end walls of the chaplet to be produced, a core-die extending transversely across the width of the bed-die and adapted to move downwardly into the recess thereof 110 and bend a strip of metal overlying the recess to form the bottom and upstanding walls of the chaplet, a wiper disposed above the bed-die and at one side of said recess and adapted to move inward over the rear of 115 the bed-die and bend down one of said upstanding walls so as to form a portion of the top of the chaplet, a wiper disposed above the bed-die at the side of the recess opposite the first-mentioned wiper and 120 adapted to move inward and bend down the remaining upstanding wall of the chaplet whose first upstanding wall was bent down by the first-mentioned wiper, and mechanism for moving the core-die and 125 wipers for shifting a partially formed chaplet forwardly on the core-die to bring it from the field of action of the first wiper to the field of action of the second wiper, combined substantially as set forth. 130

6. A chaplet machine comprising in its mechanism, a core-die completely around which the chaplet material is to be bent, and a stripper surrounding the core-die and adapted to shift a chaplet forward to a new field of operation upon the core-die, the core-die having a length at least twice the width of the chaplet to be produced, combined substantially as set forth. 7
10. 7. A chaplet machine comprising in its mechanism, a core-die on which the chaplet material is to be bent, and a stripper co-acting with the core-die and adapted to shift a chaplet forward upon the core-die, the core-die having a length in excess of the width of the chaplet to be produced, and being provided with a longitudinal slot open at its top to permit the presence and shifting of a bridge in a chaplet completely surrounding the core-die, combined substantially as set forth. 15
15. 8. A chaplet machine comprising in its mechanism, a fixed lower shear-blade, a movable upper shear-blade, a table on which a strip of metal may rest in passing to and between the shear-blades, and a spring secured to said table and having a free end near the shear-blades and adapted to support the strip of metal in a plane above the level of the lower-shear-blade and to yield when the upper shear-blade makes its active shearing motion, combined substantially as set forth. 20
25. 9. A chaplet machine comprising in its mechanism, a fixed lower shear-blade, a movable upper shear-blade, a table on which a strip of metal may rest in passing to and between the shear-blades, a spring secured to said table and having a free end near the shear-blades adapted to support the strip of metal in a plane above the level of the lower shear-blade and to yield when the upper shear-blade makes its active shearing motion, and a loop carried by the free end of the spring and adapted to limit the rising of the strip of metal as it approaches the shear-blades, combined substantially as set forth. 30
30. 10. A chaplet machine comprising in its mechanism, a bed-die having a recess as deep as the chaplet to be formed, and a pair of wipers pivoted on axes below and at the sides of the bed-die and disposed normally above the bed-die and adapted to swing inwardly and downwardly over the bed-die, combined substantially as set forth. 35
40. 11. A chaplet machine comprising, a vertically reciprocating crosshead provided with a socket having a horizontal axis, a bed-die disposed entirely in front of the plane of said crosshead and having a horizontal recess in its upper surface, a block secured removably in the recess of the crosshead, a core-die adapted to the recess in the bed-die and having its heel rigidly secured to said block and having the balance of its length free from attachment, and a main crosshead disposed in front of the first-mentioned crosshead and adapted to co-operate with the bed-die and core-die, combined substantially as set forth. 45
45. 12. A chaplet machine comprising in its mechanism, a bed-die, a vertically movable main crosshead over the bed-die, a top-die carried by said main crosshead, a secondary crosshead disposed at one side of the bed-die and top-die, a core-die carried by the secondary crosshead, a flange projecting under a portion of the main crosshead from the secondary crosshead, and a spring compressed between said flange and the part of the main crosshead above it, whereby the two crossheads, may descend together and then the main crosshead continue its descent after the movement of the secondary crosshead has been arrested, combined substantially as set forth. 50
50. 13. A chaplet machine comprising in its mechanism, a bed-die, a vertically movable main crosshead over the bed-die, a top-die carried by said main crosshead, a secondary crosshead disposed at one side of the bed-die and top-die, a core-die carried by the secondary crosshead, a flange projecting under a portion of the main crosshead from the secondary crosshead, a spring compressed between said flange and the part of the main crosshead above it, whereby the two crossheads may descend together and then the main crosshead continue its descent after the movement of the secondary crosshead has been arrested, and means for adjusting the resisting tension of said spring, combined substantially as set forth. 55
55. 14. A chaplet machine comprising in its mechanism, a pair of pivoted wipers, arms connected with said wipers and projecting toward each other, a rod adapted to slide vertically between the end of said arms, a slotted yoke on the end of said rod and engaging studs in said arms, a spring supporting said rod and serving to hold the wipers in their most separated position, and a cam for depressing the rod against the resistance of said spring and serving to move the wipers toward each other, combined substantially as set forth. 60
60. 15. A chaplet machine comprising in its mechanism, a pair of pivoted wipers, arms connected with said wipers and projecting toward each other, a rod adapted to slide vertically between the end of said arms, a slotted yoke on the end of said rod and engaging studs in said arms, a spring supporting said rod and serving to hold the wipers in their most separate position, a cam for depressing the rod against the resistance of said spring and serving to move the wipers toward each other, and a spring serving to cushion the motion of said rod in its return after said cam has acted upon it, combined substantially as set forth. 65

16. A chaplet machine comprising in its mechanism, a bed-plate, a crosshead reciprocating at right angles to the face of the bed-die, a core-die carried by the crosshead and projecting over the bed-die, a stripper surrounding the core-die, a frame carrying said stripper, a crank-shaft disposed above the level of the core-die, a rock-shaft having arms engaging pins on the stripper-frame, 5 and an arm projecting from said rock-shaft, a rotating member carried by the crank-shaft, a projection from the side of said rotating member adapted to engage said arm and bring about the movement of the stripper 10 upon the core-die, and a spring serving to return the stripper to normal position, combined substantially as set forth. 15
17. A chaplet machine comprising in its mechanism, a bed-plate, a crosshead reciprocating at right angles to the face of the bed-die, a core-die carried by the crosshead and projecting over the bed-die, a stripper surrounding the core-die, a frame carrying said stripper, a crank-shaft disposed above the 20 level of the core-die, a rock-shaft having arms engaging pins on the stripper-frame, an arm projecting from said rock-shaft, a rotating member carried by the crank-shaft, a roller journaled in the side of said rotating 25 member with its axis at right angles to the axis of the crank-shaft and adapted to engage said arm and bring about the movement of the stripper upon the core-die, and a spring serving to return the stripper to normal position, combined substantially as 30 set forth. 35
18. A chaplet machine comprising in its mechanism, a bed-plate, a cross-head reciprocating at right angles to the face of the bed-die, a core-die carried by the cross-head and projecting over the bed-die, a stripper surrounding the core-die, a frame carrying said stripper, a crank-shaft disposed above the level of the core-die, a rock-shaft having arms engaging pins on the stripper-frame, an arm projecting from said rock-shaft, a rotating member carried by the crank-shaft, a roller-carriage mounted for radial adjustment in the side of said rotating member, and a conical roller mounted in said carriage and adapted to engage said 40 45 50
- arm and bring about the movement of the stripper upon the core-die, and a spring serving to return the stripper to normal position, combined substantially as set forth. 55
19. A chaplet machine comprising, a main frame, a bed-die supported thereby, a main crosshead mounted for vertical reciprocation above the bed-die, a top-die carried by said main crosshead, a secondary crosshead 60 mounted at one side of the top-die and bed-die, a core-die carried by the secondary crosshead and projecting between the bed-die and top-die, a spring connecting the main and secondary crossheads to permit the main crosshead to continue its motion after the secondary crosshead has come to rest, a shear at the stock-entering side of the bed-die, a crank-shaft, a connection from the crank of said crank-shaft to said main 65 crosshead, a shearing cam carried by the crank-shaft, connections between the shearing cam and the shear to bring about the actuation of the shear at each turn of the crank-shaft, a pair of wipers moved inwardly and downwardly over the bed-die, a wiper-cam on the crank-shaft, connections between the wipers and the wiper-cam to cause the wipers to move inwardly at each turn of the crank-shaft, a stripper mounted 70 for movement on the core-die, a projection from the side of the wiper-cam, and connections between said stripper and projection to cause the stripper to be moved upon the core-die at each turn of the crank-shaft; 75 combined substantially as set forth. 80 85
20. A chaplet machine comprising in its mechanism, a bed-die, a vertically movable main crosshead over the bed-die, a top-die carried by the main crosshead, a secondary 90 crosshead disposed at one side of the top-die, a core-die carried by the secondary crosshead, and means for giving vertical motion to the two crossheads and for moving the main crosshead vertically after the 95 secondary crosshead comes to rest, combined substantially as set forth.
